UNITED STATES PATENT OFFICE.

PARIS R. FORMAN, OF CHICAGO, ILLINOIS, ASSIGNOR TO NATIONAL PNEUMATIC COMPANY, OF CHICAGO, ILLINOIS, A CORPORATION OF WEST VIRGINIA.

DOOR-OPERATING MECHANISM.

1,265,316.

Specification of Letters Patent.

Patented May 7, 1918.

Application filed August 26, 1915. Serial No. 47,512.

To all whom it may concern:

Be it known that I, PARIS R. FORMAN, a citizen of the United States, residing at Chicago, county of Cook, and State of Illinois, have made a certain new and useful Invention in Door-Operating Mechanism, of which the following is a specification.

This invention relates to door operating mechanism of the motor driven class.

10 The object of the invention is to provide a motor actuated door operating mechanism with a yielding or shiftable connection between the motor and door to permit a partial opening of the door and its operating 15 connections in case the door, in closing, encounters an obstruction in its path.

A further object of the invention is to provide a mechanism of the nature referred to which will permit a partial opening 20 movement of the door or a relative movement of the door and its operating devices in case the door in closing encounters an obstruction in its path, without disturbing or arresting the operation of the motor, or 25 its control devices.

A further object of the invention is to provide for a partial or relative movement of the door with relation to its operating 30 connections to the motor without arresting the motor while employing a motor of the gear type to operate the door moving connections.

A further object of the invention is to provide means for securing a relative movement of the door and its operating connections with a motor or engine of the geared type.

Other objects of the invention will appear more fully hereinafter.

40 The invention consists substantially in the construction, combination, location and relative arrangement of parts all as will be more fully hereinafter set forth, as shown in the accompanying drawing, and finally 45 pointed out in the appended claims.

In the drawing,

50 figure 1 is a view in side elevation, parts broken off, showing the application of a yielding connection between a door and its operating motor, and the operation of the same.

Fig. 2 is an end view of the structure shown in Fig. 1.

In the operation of doors and other devices, and particularly of doors employed 55 on subway, elevated, surface and other cars, it is desirable to avoid possible injury to passengers or others due to being caught between the door and the jamb of the doorway during the closing movement of the 60 doors. The danger of injury due to this cause is particularly present in the case where doors are moved to open and closed positions by motor driven devices. It is a common practice to employ a yielding shoe 65 on the advancing edge of the door, which, when an obstruction is encountered by the door during its closing movements, telescopes upon the door, and to utilize the relative movement of the door and its shoe to 70 arrest or reverse the motor or to disconnect the door from its operating connections with the motor. Various arrangements embodying this idea have been employed. The use of a telescoping shoe, however, involves 75 expense in manufacture, installation and up-keep, besides introducing elements of uncertainty of operation due to possible derangement of the connections controlled thereby.

80 Moreover, it has been found in practice that a motor or engine of the geared type, that is, a motor or engine which actuates a gear through which the door moving arm is actuated, is a more rugged device to employ 85 in connection with door operating mechanism, is more easily maintained, less expensive to manufacture and operate, and more desirable for such use.

It is among the special purposes of my 90 present invention to provide means to secure a relative or yielding movement of the door and its operating connections to the motor, and, in a somewhat more limited statement, to a motor of the geared type, thereby dispensing with the use of the yielding shoe 95 and its attendant complications and disadvantages.

In carrying out my invention I propose to employ a motor actuated operating arm for 100 moving the door to open and closed positions and to provide means to secure a limited

yielding or relative movement of the arm and its operating connections, and to employ a motor of the geared type to operate the arm.

5 In order to illustrate a practical application of the principles of my invention, though in the broad scope of my invention I do not wish to be limited or restricted to the particular form or type of motor, I have 10 shown a pneumatic motor employing a cylinder 3 employing pistons connected together by a rack 4, which meshes with and rotates a gear 5, mounted on a shaft 6. Upon this shaft is mounted a disk 7, having an 15 arm portion 8 extending therefrom. Carried by the member 7 adjacent to its edge at one side of its center is a bearing lug 9. A rod 10 is mounted to slide freely at one end through the lug 9, the other end of said 20 rod being suitably connected to the door 11 preferably through a loose sliding connection in the usual manner, as indicated at 12. The rod 10 carries a collar 13 between which and the bearing lug 9 is interposed a spring 14, 25 which, if desired, may be conveniently coiled upon the rod 10, and the tension of which is normally exerted to urge said rod longitudinally toward the door. A link 15 is pivotally connected at one end to the free end of 30 the arm 8, and at the other end to the rod 10, and through which the rod is swung when the motor is actuated.

The operation is exceedingly simple. When the motor is operated the shaft 6 and 35 with it the member 7 is rotated. Through the arm 8 and link 15, the door connection or rod 10 is swung, as indicated in the dotted line position shown in Fig. 1, to open or close the door. If, however, the door in 40 closing, encounters an obstruction in its path, the door closing movement will be arrested although the motor continues its door closing operation. Instead of this action causing an increasing pressure on the obstruction 45 thereby causing an injury to an arm, leg, foot or other portion of the body of a passenger, for instance, the rod 10 will yield endwise against the tension of spring 14, said rod sliding through the bearing lug 9, 50 thereby relieving the obstruction of the danger of injury through increasing pressure and permitting the same to be extracted or withdrawn, without injury from between the door and its jamb, or, if desired, in case the 55 door is closed, or at any point in its closing movement, by exerting pressure on the door tending to move it toward open position the rod 10 will be shifted endwise against the tension of spring 14 thereby permitting relative movement of the door and its connections with the motor actuated drive devices. Since the spring 14 serves only to maintain 60 normally the rod 10 pressed endwise to-

ward the door it may be made comparatively light thereby permitting the easy relative 65 movement of the door and its motor drive connections without requiring the expenditure of excessive effort or pressure.

It will be observed that the power to swing the rod 10 is transmitted to it mainly 70 through the arm 8 and link 15. This link, in the opening movement of the door pushes the rod 10, and, by reason of the angular relation of the link and arm 8, the tendency of the pushing action is to keep the rod 10 75 pressed endwise toward the door while accomplishing its door opening function. In the closing movement, however, the link 15 exerts a pull on the rod 10, the tendency of which is to keep the rod pressed endwise 80 against the tension of spring 14, thereby, to some extent, overcoming the tension of said spring and hence rendering the relative movement of the door above referred to more easy of accomplishment in case the 85 door in closing encounters an obstruction. Such relative movement of the door, or rather, the endwise movement of the rod 10 is indicated in the heavy dotted line position of the parts of Fig. 1, the pivoted link permitting such movement of the rod by rocking about its pivoted point of connection to the free end of arm 8. In order to limit the extent of yielding endwise movement of rod 10, a stop 16 is provided on arm 8 which 90 forms an abutment against which the link 15 strikes thereby preventing further endwise movement of said rod 10.

It will be observed that the bearing lug 9 is so positioned relative to the shaft 6 that 95 their geometric axes are approximately in the same horizontal plane. By so designing the parts that the longitudinal axis of rod 10, when the door is closed, is downwardly inclined from the bearing lug 9 below the said horizontal plane of the axes of 100 said lug and shaft 6, an efficient lock is formed to hold the door in its closed position. In starting the door toward its completely closed and locked position as shown 105 in full lines in Fig. 1, the initial tendency of the movement of arm 8 and link 15 on rod 10 is to slightly shift the rod 10 endwise against the spring 14, thereby relieving the pressure under which the parts, acting as a 110 lock, hold the door closed. After the horizontal dead center line of the rod 10 and axes of shaft 6 and lug 9 has been passed, however, this tendency is overcome and the 115 normal opening action is resumed. This provides for an efficient locking arrangement for the door when closed as well as an 120 easy release of the lock in opening the door.

From the foregoing description it will be seen that I provide an exceedingly simple 125 and efficient motor actuated door operating

mechanism which permits the door to be easily shifted or moved relative to the connections with its driving motor or, as the equivalent thereof, the door may be arrested 5 without arresting or reversing the motor or detaching the door driving connections. It will also be seen that the desired relative movement of the door is secured at whatever point in its closing movement it may 10 encounter an obstruction, and that the door may be partially opened by hand when closed without disturbing the motor or the door operating connections thereto, and that these various advantages are secured in a 15 mechanism employing a motor of the geared type.

Many variations and changes in details 20 may readily occur to persons skilled in the art without departing from the spirit and scope of my invention as defined in the claims.

Having now set forth the object and nature 25 of my invention and a construction embodying the principles thereof, what I claim as new and useful and of my own invention and desire to secure by Letters Patent is,—

1. In a door operating mechanism, a motor, a rock arm operated thereby, a door 30 moving rod, a connection between said arm and rod to swing the latter, and a separate connection between said motor and said rod.

2. In a door operating mechanism, a motor, a rock arm operated thereby, a door 35 moving rod, a connection between said arm and rod to swing the latter, and a separate slidable connection between said motor and said rod.

3. In a door operating mechanism, a motor, a rock arm operated thereby, a door 40 moving rod, a connection between said arm and rod to swing the latter, and a separate connection between said motor and said rod, said rod being yieldable to pressure exerted 45 against the edge of the door.

4. In a door operating mechanism, a motor, a rock arm operated thereby, a door moving rod, a connection between said arm and rod to swing the latter, and a separate 50 slidable connection between said motor and said rod, said rod being yieldable to pressure exerted against the edge of the door relative to said motor through said slidable connection.

5. In a door operating mechanism, a motor, a rock member actuated thereby, a rod 55 connected to the door slidably connected to said rock member, a yielding tension interposed between the rod and the rock member

60 and a link pivotally connected to the rod and rock member to swing the latter independently of the slidable connection between said rod and rock member.

6. In a door operating mechanism, a motor, a rock shaft actuated thereby, a member 65 mounted on said shaft and having a bearing lug at one side of the rock axis thereof, a rod extending loosely through said lug and connected to the door, means to yieldingly urge said rod toward said door, and a link 70 connecting said rod and said rock member.

7. In a door operating mechanism, a motor, a rock shaft actuated thereby, a member mounted on said shaft and having a bearing lug at one side of the rock axis thereof, a rod 75 extending loosely through said lug and connected to the door, a spring coiled on said rod and operating to yieldingly urge the rod endwise toward the door, and pivotal connections between the rod and rock member 80 to swing the former.

8. In a door operating mechanism, an actuating member having a bearing lug, a rod mounted to slide freely through said lug, said rod being pivotally connected to the 85 door, a collar carried by said rod, a spring interposed between said collar and said lug, a separate connection between said actuating member and said rod, and means to move 90 said actuating member.

9. In a door operating mechanism, an actuating member including a bearing lug, a rod having a collar thereon and extending at one end freely through said lug and pivotally connected at its other end to the door, 95 a spring surrounding said rod and interposed between said collar and said lug, a separate connection between said actuated member and said rod, and means to operate 100 said actuating member.

10. In a door operating mechanism, a motor, a rock shaft actuated thereby, a member mounted on said shaft and having a bearing lug at one side of the rock axis thereof, the axes of said lug and shaft being in substantially a horizontal plane when the door is closed, a longitudinally shiftable spring 105 pressed rod passing through said lug and connected to the door, and operating connections between said rod and rock member, 110 the longitudinal axis of said rod being downwardly inclined to the plane of said axes when the door is closed.

11. In a door operating mechanism, a motor, a rock shaft actuated thereby, a member 115 carried by said shaft and having a bearing lug, a longitudinally shiftable rod passing through said lug and engaging the door, means carried by said rod for normally urging said rod toward said door, and driving 120 connections between the rod and said member.

12. In a door operating mechanism, a motor, a rock shaft actuated thereby, a member carried by said shaft and having a bearing 125 lug, a longitudinally shiftable spring pressed

rod passing through said lug and engaging the door, and driving connections between the rod and said member.

13. In a door operating mechanism, a motor, a rock member actuated thereby, a spring pressed rod connected to the door and end-wise movable relative to the rock member, a link pivotally connecting the rock member

and rod, and a stop to limit the rocking movement of the link relative to the rock member.

In testimony whereof I have hereunto set my hand on this 12th day of August A. D., 1915.

PARIS R. FORMAN.
